UNITED STATES PATENT OFFICE.

VINCENZO AVOLIO AND FERDINANDO LATTANZI, OF PORTLAND, OREGON.

SANDING MACHINE.

1,417,293.

Specification of Letters Patent. Patented May 23, 1922.

Application filed April 27, 1921. Serial No. 464,865.

To all whom it may concern:

Be it hereby known that we, VINCENZO AVOLIO and FERDINANDO LATTANZI, respectively a subject of the King of Italy, (who 5 has declared his intention of becoming a citizen of the United States,) and a citizen of the United States, residents of Portland, in the county of Multnomah and State of Oregon, have invented a new and useful 10 Sanding Machine, of which the following is a specification.

This invention relates more particularly to machines for sanding edges of table tops with sand paper belts.

15 The objects of our invention are to provide an exceedingly simple and efficient machine to be used in connection with a belt sander which will render it possible to eliminate a great deal of work that is now performed manually.

We accomplish these results in the manner set forth in the following specification and illustrated in the accompanying drawing, in which:

25 Figure 1 is a front elevation of our machine set up for one class of work. Figure 2 is a side elevation of Fig. 1. Figure 3 illustrates the manner in which the machine finishes moulded edges. Figure 4 is a partial 30 plan showing the construction of the frame of the machine. Figure 5 is a front elevation showing the machine handling a different class of work. Figure 6 is a side elevation of Fig. 5. Figure 7 shows an attachment of the machine for finishing the 35 aprons of table tops. Figure 8 is a plan of Fig. 7.

Figure 9 is a vertical section along the line 9—9 in Figure 10.

40 Figure 10 is a horizontal section along the line 10—10 in Figure 9.

Similar numbers of reference refer to the same or similar parts throughout the several views.

45 Referring in detail to the drawing, we have constructed our machine as shown in the drawings in which the device is mounted over a pit 10 on a pair of tracks 11 which are mounted underneath at right angles to 50 a sand belt 12 passing over the pulleys 13, such as are in common use.

A rectangular frame 14 is supported by the rollers 15 on the tracks 11 and rendered rigid by the interior braces 16, see Figure 4.

55 Near the forward side of the frame 14 we have hinged a table member 17 formed of

boards secured to the members 18 which are joined by bolts 19 to the frame 14. The braces 20 hold the table 17 in any desired relation to the frame 14 by means of the 60 bolts 21 and 22 which are placed in the corresponding holes 23.

On the front side of the table 17 we have placed a turn-table 24 provided with suitable spherical rollers 25 and pivoted on a 65 bolt 26 which passes through any one of the holes 27 in the table 17 and the reinforcing member 28. The various holes 27 are used for the various sizes of work encountered in bringing them within range of 70 the sand belt 12. Suspended from the table 17 are the two hangers 29 on whose lower ends are attached the grooved rollers 30. The hangers 29 are also susceptible to vertical adjustment.

75 Across the projecting ends 31 of the braces 20 we have placed a round bar 32 hinged at the pivot 33 and hooked upon the shouldered pin 34. This bar 32 is utilized in moving the machine along its track 11 80 and also to support the roller 35 by means of the rod 36.

The form of the machine just described is used in sanding the edges of a completed circular table top 37 which is held against 85 the turntable 24 by means of the roller 35 and supported by means of the rollers 30. It will be evident that it is now a simple matter to bring the sand belt 12 down by means of the block 12^B to the edge of the 90 table top 37, and by rotating the top its entire circumference may be finely sanded in a very short space of time.

This same machine is used to sand the 95 aprons by substituting the frame 38 shown in Fig. 7 which is mounted on the cross spokes 39 in place of the table top 37. The apron 40 to be sanded is inserted under a lip 41 on the frame 38 and is then pressed securely against the points 42 projecting from the frame 38. 100 The method of sanding the surface of this apron 40 is exactly the same as described for the edge of the table top 37. A hand rail 43 is attached to the frame 38 to facilitate its rotation.

105 Turning now to Figures 1 and 2 we have illustrated the same device, but have left off the rollers 30 and have attached instead a semi-circular board 44 of a somewhat smaller diameter than are the half round table tops 110 to be sanded in the following operation. These tops have a grooved edge which has

hitherto been sand papered by hand with the expenditure of a great amount of labor. In this case we also employ the sand belt 12^A, which is sufficiently narrow to enter the 5 groove 45. It is evident that a partial rotation of the part table top 46 containing the groove 45 will easily expose the groove to the action of the sand belt 12^A. It will be understood that the bolt 26 of the turntable 24 must 10 be placed in the proper hole 27 in order to provide a working radius equal to that of the work 46.

When it is desired to finish a moulded edge 47 similar to the one shown in Fig. 3 it is desirable to tip the table 17 toward the angle shown in dotted lines as 18^A, which is accomplished as previously explained by the changing of the bolts 21 and 22. A narrow sand belt 12^A is also used in this operation 20 which permits the bringing of the belt up close to the shoulder 48 by means of the block 49, which is shaped to fit the moulded edge 47.

It will be understood that in sand papering the moulded ends of table leaves instead 25 of the rounded ends previously referred to it will be necessary to prevent the table 17 from rotating. This may be accomplished by removing the table altogether or by the 30 insertion of clamping bolts 50. In most cases, however, the provision of dowels 51 on the edge of the member 44, or its equivalent, will be sufficient to hold the work against the table. Otherwise the usual 35 means for holding work in place may be employed as desired.

It will be understood that the turn table 24 is rotated by hand at the will of the operator, and by means of this turn table the 40 articles which are clamped or held against same may be exposed to the action of the sand belt. The rollers 25 are used merely to reduce the friction between the turn table 24 and the table 17. The rollers 30 are made 45 adjustable in order that the work may be properly centered upon the table 24.

The frame 38 is placed centrally upon the turn table 24 and clamped to same with bolts through the holes 27. This of course is only used for sanding the aprons 40.

While we have thus illustrated and described our invention it is not our desire to limit ourselves to this precise form or method of application, but we intend that it shall cover all forms and modifications 55 that fall fairly within the appended claims.

What we claim as new is:

1. In a sanding machine, the combination of a sanding belt with a track under and at right angles to said belt, a carriage on said track, a tiltable turn-table mounted on said carriage, a pair of adjustable rolls on said carriage adapted to support a circular object concentrically with and alongside of said turntable, and a clamping means for holding said circular object against the turntable.

2. The combination of a sanding belt with a track under same, a pit under said track, a carriage on said track, a tiltable table 70 hinged at one side to said carriage and secured in any position by angular braces adjustably attached to said carriage and table, a turntable rotatable by hand mounted against said table, roller means adjustably 75 attached to said tiltable table and projecting in front of said turntable, and a clamp means consisting of an arm adapted to bear against the under side of a table top at its center and hold same against the turntable 80 in a manner that the turntable and the table top may be rotated together by hand.

3. In a sanding machine, the combination of a sanding belt, a track under said belt, a carriage on said track, a tiltable turntable 85 on said carriage, a stop on said turntable adapted to hold semicircular boards concentrically against said turntable in a manner that said belt may be brought down against the edge of said board.

VINCENZO AVOLIO.
FERDINANDO LATTANZI.
